UNITED STATES PATENT OFFICE.

JAMES E. SHEAFFER, OF BURNHAM, PENNSYLVANIA, ASSIGNOR OF FORTY-FIVE ONE-HUNDREDTHS TO ALBERT B. LONG, OF LEWISTOWN, PENNSYLVANIA.

HYDROCARBON-BURNER.

1,140,621.

Specification of Letters Patent.

Patented May 25, 1915.

Application filed December 17, 1914. Serial No. 877,718.

To all whom it may concern:

Be it known that I, JAMES E. SHEAFFER, a citizen of the United States, residing at Burnham, in the county of Mifflin and State of Pennsylvania, have invented a new and useful Hydrocarbon-Burner, of which the following is a specification.

The present invention appertains to hydrocarbon or liquid fuel burners, and aims 10 to provide a novel and improved appliance of that character.

This invention contemplates the provision of a hydrocarbon burner of unique construction, to enhance the utility and the efficiency thereof, and whereby the fuel will be thoroughly atomized and admixed with air, to provide a highly combustible mixture.

It is also the object of the invention, to 20 provide a hydrocarbon burner of such construction, as to enable the air to be admitted or introduced in a novel manner, for thoroughly mixing and agitating the fuel and air, and whereby the supply of air may be 25 regulated.

It is also within the scope of this invention, to provide a hydrocarbon burner of the nature specified, which will be comparatively simple, compact, non-encumbering 30 and inexpensive in construction, as well as being convenient, practical and serviceable in its use.

With the foregoing and other objects in view which will appear as the description 35 proceeds, the invention resides in the combination and arrangement of parts and in the details of construction hereinafter described and claimed, it being understood that changes in the precise embodiment of 40 the invention herein disclosed can be made within the scope of what is claimed without departing from the spirit of the invention.

The invention is illustrated in its preferred embodiment in the accompanying 45 drawing, wherein:—

Figure 1 is an elevation of the improved burner, partly in section. Figs. 2 and 3 are cross sectional views taken on the lines 2—2 and 3—3, respectively, of Fig. 1.

50 In carrying out the invention, there is provided a frusto-conical or tapered casing or body 1, having its largest end disposed forwardly, and having the inner integral nozzles 2 and 3 between its ends. The noz-

zles 2 and 3 project forwardly, the nozzle 2 being disposed in advance of the nozzle 3, and the nozzle 3 being slightly smaller than the nozzle 2 and projecting into the basal or rear portion of the same. The forward end or tip of the nozzle 2 projects through 55 the forward or largest end of the casing 1. The rear or smallest end of the casing 1 is provided with a reduced portion or boss 4, forming a rearwardly facing shoulder 5, and the casing 1 is also provided with three 60 annular series of slots or air inlets 6, 7 and 8. The slots 6 are disposed between the basal portion of the nozzle 2 and the forward end of the casing, and the slots 7 are disposed between the basal portions of the 65 nozzles 2 and 3, while the slots 8 are disposed between the basal portion of the nozzle 3 and the rear end of the casing 1. The forward end of the casing 1 is provided with 70 an outturned annular flange 9 having the 75 annular lip or rim 10.

A refractory discharge nozzle 11 which is of frusto-conical or forwardly tapered form, has its largest or basal end seated against the forward end of the casing 1, and provided with an outstanding annular flange 12 fitting within the lip or rim 10 of the flange 9, and a ring or annulus 13 of angular cross section is fitted over the basal portion and flange 12 of the nozzle 11 to coöperate with 80 the flange 9 and its lip or rim 10 for clamping the basal flange 12 of the nozzle 11 in place. Bolts or other securing elements 14 are engaged through the ring or annulus 13 and the flange 9, for clamping the parts together and whereby when the bolts 14 are loosened and removed, the parts may be 85 separated.

A frusto-conical or tapered shell or sleeve 15 is mounted for rotation upon the casing 95 or body 1, and is preferably provided with an outstanding handle or finger piece 15^a for enabling the shell 15 to be readily swung to open and closed positions. The oscillatory movement of the shell 15 is preferably 100 limited by means of an arcuate slot 16 provided in the shell 15, and a stud or lug 16^a secured to the casing 1 and extending through the slot 16. The shell 15 provides an air regulator, it being provided with 105 three annular series of slots or openings 17, 18 and 19 coöperating with the respective slots 6, 7 and 8 of the casing 1 to be brought

into and out of registration therewith as the shell or regulator 15 is swung back and forth.

The casing is of circular cross section and 5 has a smooth periphery whereby the shell is rotatable snugly upon the casing for opening and closing the air inlets of the casing.

The forward or largest end of the shell or regulator 15 abuts against the flange 9 of 10 the casing 1, and a retaining nut 20 is threaded upon the reduced end 4 of the casing 1 and bears against the rear or smallest end of the shell 15 for mounting the same rotatably in place upon the casing. When 15 the nut 20 and stop or lug 16^a are removed, the shell or regulator 15 may be moved off of the casing 1.

A tubular steam or pressure fluid nozzle 21 has a portion 22 between its ends threaded 20 through the smaller end of the casing 1 and having its tip 23 projecting forwardly within the casing into the basal portion of the nozzle 3, the nozzle 21 having a restricted or contracted portion 24 in rear of the tip 23, and also having an oil or liquid fuel inlet or branch 25 immediately in rear of the restricted portion 24 and arranged at an acute angle to the nozzle 21.

The nozzles 21, 3, 2 and 11 are co-axial 30 and arranged in a longitudinal series, with the tip of the nozzles 21, 3 and 2 projecting into the basal portions of the respective nozzles immediately in advance thereof. The nozzles 21, 3, 2 and 11 are also increased 35 in size in succession. The parts of the burner may be readily cast from metal, or formed in any other suitable manner, and may be readily assembled with one another, as well as being readily separable for purpose 40 of cleaning, repair or replacement.

In use, the steam or pressure fluid and liquid fuel or oil pipes are attached to the nozzle 21 and branch 25, respectively. Then, as the steam or pressure fluid is admitted 45 through the nozzle 21 it will be directed axially forward through the nozzles 2, 3 and 11 successively, and the passage of the steam through the nozzle 21 will draw a jet or stream of oil or liquid fuel through the branch 25, it being noted that the steam in passing through the restricted or contracted portion 24 of the nozzle 21 will create a suction 50 extending through the branch 25 for causing the fuel to be drawn into the nozzle 21 and casing 1 with the steam. Now, when the steam is discharged from the nozzle 21 it will atomize the fuel, and the mixture be-

ing directed through the nozzle 3, will create a suction between the nozzle 3 and tip 23 of the nozzle 21, so that air will be drawn 60 through the registering slots 8 and 19 and mixed with the steam and fuel. Similarly, when the mixture is discharged from the nozzle 3 through the nozzle 2, air will be drawn inwardly between the nozzles 2 and 65 3 through the registering slots 7 and 18, and in a like manner, when the mixture passes from the nozzle 2 through the nozzle 11, air will be drawn through the slots 6 and 17 to flow between the nozzles 2 and 11 to 70 admix with the mixture discharged from the nozzle 2. The final mixture is discharged from the nozzle 11 to support the flames, it being understood that the present burner may be employed for heating boilers, furnaces, and the like, or in any other suitable 75 capacity.

Due to the construction of the present burner, streams of air will be admitted 80 through the slots of the casing and shell or regulator and will pass through the annular spaces between the concentric nozzles, to admix with the steam and atomized fuel, to thoroughly agitate and mix the steam, air and fuel for providing a highly combustible 85 mixture. The amount of air admitted into the casing may be regulated by swinging or adjusting the shell or regulator 15 to bring the slots thereof more or less out of registration with the slots of the casing 1. 90

The present burner may not only be employed for burning liquid fuel, but may also be employed for burning pulverized coal, and similar substances.

What is claimed is:

A hydrocarbon burner embodying a casing having a nozzle therein projecting toward one end, said end of the casing having an outturned annular flange provided with an annular lip, a discharge nozzle having its basal end seated against said end of the casing and provided with an outstanding annular flange fitting within said lip, a ring of angular cross section fitting over the basal portion and flange of the discharge nozzle, 100 and securing elements engaged through said ring and first mentioned flange.

In testimony that I claim the foregoing as my own, I have hereto affixed my signature in the presence of two witnesses.

JAMES E. SHEAFFER.
